UNITED STATES PATENT OFFICE.

CHARLES H. ROYCE AND CHARLES H. ALLEN, OF CHICAGO, ILLINOIS, ASSIGNEES TO THE HARDEN-HAND-GRENADE FIRE-EXTINGUISHER COMPANY, OF SAME PLACE.

DESIGN FOR A BOTTLE.

SPECIFICATION forming part of Design No. 15,496, dated October 28, 1884.

Application filed August 13, 1884. Term of patent 14 years.

To all whom it may concern:

Be it known that we, CHARLES H. ROYCE and CHARLES H. ALLEN, citizens of the United States, residing at Chicago, in the county of Cook, State of Illinois, have invented and produced a new and original Design for the Bottles of Hand-Grenade Fire-Extinguishers, of which the following is a specification.

The accompanying wood-cut illustrates our design, being a view of the same in elevation.

The body of the bottle, which is of general spherical shape, has plane or truncated portions A at opposite points around its circumference, and has at its base the projections B. From the top of the body rises the long neck C, having the circumferential enlargement c below its slightly-flaring top c'. Around the top of the body of the bottle, at the base of the neck, are the concentric rings or circles D, and on the surface of the body are preferably the lozenge-shaped elevations E, formed by the intersecting grooves e.

We claim—

The design for the bottle of a hand-grenade fire-extinguisher herein shown and described, the same consisting of the bottle having the truncated portions A, the projections B at the base, the long neck C and circumferential enlargement c, flaring top c', the concentric rings D, and the lozenge-shaped elevations E.

In testimony whereof we have hereunto set our hands in presence of two subscribing witnesses,

CHARLES H. ROYCE.
CHARLES H. ALLEN.

Witnesses to the signature of Charles H. Royce:

H. T. METCALF, Jr.,
A. T. S. ANDERSON.
